AUTOMATIC DOOR LATCH RELEASE SYSTEM

Michael L. Thomas, Sr., and Michael L. Thomas,
Jr., Lenoir City, Tenn.

Application March 26, 1948, Serial No. 17,176

6 Claims. (Cl. 292—33)

1
This invention relates to an automatic door latch release system, and particularly to such a system in which the opening of one door causes release of a latch on a second door, and vice versa.

The main object is to provide a pair of doors for a bath room which individually have locks or latches, for example, with a two-way automatic system for releasing the lock or latch of one door when the other door is opened, so that both doors are automatically opened by merely opening one of the two.

Another important object is to provide one of a pair of doors for a room with a special latch, and the other door with a latch-releasing device operated by opening the latter door and connected to the special latch on the first-mentioned door in such manner as to open the special latch upon being thus operated.

An ancillary object is to provide each of a group of doors for a room with a latch and an operating device, with the operating device on one door connected to the latch on each other door.

A further object is to have a two-way latch-releasing system as indicated which provides for individual and independent locking or latching each of the two doors without interference from the releasing system, but instead automatically setting the latter for operation.

It is also an object to have such a two-way latching-releasing system which is simple to install and so simple to operate that it requires substantially no attention and is virtually automatic at all times.

Other objects and advantages will be disclosed in greater detail as the subjoined specification proceeds.

As it is desired to bring out comprehensively the features of the invention to enable a person skilled in the art to make and use the latter, it is illustrated in the accompanying drawings forming part hereof, and in which:

Figure 1 is a side elevation of a pair of doors of a bath room, for example, on a greatly reduced scale, including an automatic two-way latch and latch-releasing system made according to the invention and embodying the latter in practical form;

Figure 2 is an enlarged fragmentary section of a latch-releasing device of Figure 1, showing interior detail;

Figure 3 is a section taken on line 3—3 in Figure 2;

Figure 4 is an enlarged side elevation of a latch

of the present invention shown partly in section to disclose structural details;

Figure 5 is a section of the latch taken on line 5—5 in Figure 4.

5 In the five figures, the same reference numerals indicate the same or identical parts.

When a room has two doors, as for example a bath room, it is quite obvious that both doors are necessarily latched or locked when the room is occupied, but that it is quite as obvious that when the occupant leaves this room, he should unlock both doors and not only the one door through which he leaves the room. However, it happens all too often that this point is forgotten, and only the door used to leave the room is unlocked, while the other door remains locked, making it necessary for a person attempting to enter the room through the latter to go around through other rooms to reach the open door.

10 This, of course, is most annoying and often inconvenient, and nonetheless wholly unnecessary according to the present invention, as will immediately be explained in full detail.

Hence, in the practice of our invention, and **15** referring now again to the drawings, a pair of mutually-independent doors 6, 7, are respectively hinged at 8, 8, 9, 9 to the door frames 10, 11 in wall 12 of a bath room or the like, and provided with more or less conventional door knobs 13, 14 and associated locks 15 and 16 adjacent door jambs 17 and 18, respectively, of the door frames. The details of the last-mentioned locks form no part of the invention, and, therefore, require no further discussion.

20 However, on door jamb 17, a special latch or bolt casing 19 is secured in place by screws, nails or the like 20, 23 and has a bolt 21 adapted to be extended into locking relation in socket 22 of door 6 to lock the latter. The mentioned socket is secured in place by screws 23, or the like, in the door (Figure 4). A stud 24 upon the latch provides means for manually operating this latch or bolt by pushing the operating stud to the right in longitudinal slot 25 until depending portion 26 of this slot is reached, as indicated at 27 in broken lines; when the stud may be pulled down into this depending portion, preventing accidental return of the bolt to the left. In a longitudinal bore 28 in latch bolt 21 is a tension spring 29 held at the inner end by a washer 30 fixed in place by a screw 31 screwed into end 32 of casing 19, and at the other end the spring is looped at 33 about stud 24; thus normally tending to withdraw bolt 21 toward the left into the latch casing out of contact with the door socket.

25 Figure 2 is a section taken on line 3—3 in Figure 2;

Figure 3 is an enlarged side elevation of a latch

Obviously, when the stud 24 is drawn down into slot portion 26, the latch bolt 21 is partly rotated in latch casing 19 so that when it is rotated back again by any means to register the stud with slot 25, spring 29 will instantly return the bolt from the position indicated in broken lines at 34 into casing 19 so that the stud again occupies its initial idle withdrawn position as shown in Figures 4 and 5. As will shortly appear, the head 35 of stud 24 has an eye 36 to which a cord or the like 37 is attached by which to release the latch or bolt just described.

In connection with the other door jamb 18 (Figures 2 and 3) is an operating frame 38 fixed in position by screws or other means (not shown), with a block 39 held in place thereon by a pair of pins 40, 40 and having an inner upwardly-projecting spring post 41 secured by attaching screws 42 to the frame, while screws 43 attach the frame by its inner lugs 44 to the inner wall 45 of door jamb 18. Projecting a distance into block 39 is a horizontal shaft 46 having a circumferential groove 47 having a rectangular cross-section into which a retaining screw 48 projects in order to prevent longitudinal shifting of the shaft during rotation, this shaft extending inwardly to the right and terminating in a bearing or pillow block 49 secured on frame 38 by screws 42 and serving as a spring post for a spring 49 mounted on the shaft whose purpose will shortly be explained. Fixed on the latter is a small bevel gear 50 with the bevel teeth 51 thereof meshing with the teeth 52 of a relatively large bevel gear 53 rotatably mounted upon the vertical stud shaft 54 projecting upward from stationary block 39 to which it may be suitably secured. The hub 55 of gear 53 is retained rotatably in assembled relation with stud shaft 54 by means of screw 56, while above the bevel teeth is a large spur gear 57 with spur teeth 58 exposed adjacent to door 7 in a horizontal slot 59 in outer wall 60 of jamb 18 and meshing with the teeth 61 of an arcuate rack 62 on the edge 63 of door 7 and having the end lugs 64 thereof secured to the door by screws 65. Thus, when the door is opened in the direction indicated by arrow 66 in Figure 3, rack 62 will cause corresponding limited rotation of spur gear 57 and bevel gear 53 beneath it in the direction of arrow 67 until the teeth 61 of the rack are brought out of contact with teeth 58 of the spur gear, the rotation being sufficient to cause substantially a complete revolution of smaller bevel gear 50 with its shaft 46.

Upon this horizontal shaft is mounted a slideable collar 68 provided at its outer end with clutch teeth 69 normally engaging with the corresponding clutch teeth 70 upon the inner end of bevel gear 53, the collar being held against the bevel gear by compression spring 49 on shaft 46 between this collar and pillow block or bearing 41. Optionally, a sleeve 71 may be mounted exteriorly of spring 49 to protect the same from dust and dirt.

Upon collar 68 is an eye 72 to which previously-mentioned cord 37 is secured, the latter being passed through plastic, porcelain, glass or metal tubular guides 73, 73 in the wall studs 74, 74 above the level of the door frames 18 and 11, brought over pulleys 75 and 76, and at the ends connected, as already described, to bolt 21 on the one hand, and to collar 68 on the other hand. The mentioned tubular guides thus could be replaced by other devices, such as screw eyes or the like, but in any case allow free sliding move-

ment of the cord in either direction through these guides.

Hence, when the opening of door 7 causes partial rotation of gears 50 and 52 with consequent rotation of smaller bevel gear 50 and with it the collar 68 and its attaching member or eye 72, the result is that a limited length of cord 37 is wound up on the collar, drawing the cord toward the right. If the latch bolt 21 at this time projects into latch socket 22 on door 6, and the latch stud 24 occupies the lower portion of vertical slot 26 in the latch casing, such a pull on cord 37 attached to eye 36 on head 35 of stud 24 will immediately raise the latter in vertical slot portion 26 until the stud is in line with slot 25 when the bolt will be suddenly withdrawn into the latch casing from door socket 22 by internal spring 29. Thus, opening door 7 will release the latch of the other door 6, so that both doors are simultaneously opened, but closing the same door 7 will cause reverse rotation of the gears by rack 62, again releasing cord 37 and producing a slack thereon which is taken up when manually locking door 6 by shifting bolt 21 against spring 29 to engage in socket 22 and drawing stud 24 down into vertical slot portion 26. Should the cord be too slack or too tight for proper cooperation between the doors as above described, the collar 68 at the right is seized and pushed toward bearing 41 against spring 49 to disengage clutch teeth 69 and 70 from each other so that the collar may be turned freely forward or backward until the cord is in correct adjustment, when the collar may be again released so that the spring 49 may cause collar teeth 69 to mesh with teeth 70 of gear 50. Both gear 50 and collar 68 may be knurled for improving the grip of the fingers thereon, if desired.

Thus far one-half of the latch-releasing system embodying the invention has been described, but as shown in Figure 1, the same system is repeated in reverse so that opening door 6 will release door 7, and vice versa. The second cord 77 passes through hollow guides 78, 78 in studs 74, 74, being connected to the bolt generally indicated at 79 and adapted to engage in socket 80 in door 7 and be retained in locked position by the bolt stud when engaging in the lower slot portion 81 of the bolt casing. The latch 79 in every respect corresponds to the latch shown and described in connection with Figures 4 and 5, and thus is manually operable to lock door 7 independently of the latch or operating devices of the other door. Such locking of the door pulls on cord 77 over pulleys 82, 83, and this takes up the slack thereof so that the other end of the cord will be pulled which is attached to and adapted to be opened by the gear-operated releasing device generally indicated at 84 engaging with rack 85 on door 6. The gearing 84 and rack 85 are in each detail substantially the same as already illustrated and described in connection with Figures 2 and 3, so that repetition here would be superfluous.

From the foregoing, it is evident that each door is readily locked by manually locking the latch bolt associated with the door jamb thereof and that either bolt may also be manually released by pushing up the stud thereof when it will snap back and release the door. However, the arrangement is such that whether this is done with one door or the other, the subsequent opening of the unlocked door will initiate operation of its associated gear-operated releasing device and thereby cause corresponding release

of the other door by unlocking the latch bolt thereof through the cord interconnecting the devices. In other words, the two latch-release systems are opposite in arrangement, and in one sense operated independently of each other, but cooperate in providing the same ultimate result that unlocking and opening either of two doors will automatically release or unlock the other door so that it may be freely opened from outside the room.

Spur and bevel gears have been described in association and cords mentioned as transferring the operation originating with these gears to latch bolts for releasing the latter; but it should be understood that we may use other gears, such as spur and crown gears in mesh, etc., and chains for transferring the operative movement thereof if desired. It should, of course, be understood that when in the foregoing description two doors have been named as cooperating in such fashion that the opening of one door automatically releases the latch or lock on the other door, the invention is not limited to application to only two doors.

Having now fully described our invention, we claim:

1. An automatic door latch-releasing system including the combination with two mutually remote doors having individual door jambs spaced a distance apart and adapted to be independently opened, of a latch means upon the jamb of one door serving to lock the latter in the locked position of the latch means, operating means upon the jamb of the other door disposed in effective position to be actuated by said other door upon opening thereof, and remotely operating transmission means transmitting motion from the operating means to the latch means and releasing the latter and thereby unlocking the first-mentioned door when the other door is opened.

2. An automatic door latch-release system including the combination with two doors having individual door jambs and adapted to be independently operated, of a latch casing upon the jamb of one door having a longitudinally-slotted portion terminating in a downwardly-directed slotted portion, a latch bolt in the latch casing having a stud projecting therefrom through the longitudinally slotted portion to be accessible for manual locking of said bolt by shifting the stud down into the downwardly-slotted portion and causing the bolt to project from the jamb into locking engagement with the door, an operating member movably mounted on the jamb of the other door, means on the latter door for actuating the operating member upon opening this other door, a wind-up member rotated by said operating member upon actuation of the latter, a cord connected at one end to the wind-up member adapted to be partly wound up thereon when it is rotated, said cord being connected at the other end to the stud on the bolt and raising said stud from the downwardly-directed slotted portion and thereby releasing said stud for movement in the longitudinally slotted portion, thus unlocking the first-mentioned door when the first-mentioned one end of said cord becomes wound partly upon the wind-up member upon opening of said other door, and means for supporting said cord intermediate the two doors for free movement thereof in either direction.

3. An automatic door latch-releasing system including the combination with two doors having independent door jambs and adapted to be individually opened, of a latch casing upon the

jam of each door having a longitudinally-slotted portion terminating in a downwardly-directed slotted portion, a latch bolt in each latch casing having a stud projecting therefrom through the associated slotted portion to be accessible for manual locking of each bolt by shifting the stud thereof down into the downwardly-directed slotted portion of the casing and causing the bolt to project from the jamb into locking engagement with the respectively adjacent door, means for returning each bolt to unlocked position when released from the downwardly-directed slotted portion, an operating member movably mounted on each door jamb, means on each door for actuating the respectively adjacent operating members upon opening the door, a wind-up member associated with and rotated by each operating member upon actuation of the latter, a pair of cords each individually connected at one end thereof to the wind-up members and each adapted to be partly wound up on the respective wind-up member to which it is connected when said wind-up member is rotated, each cord being connected at the other end thereof to the stud on the bolt adjacent to the respectively-remote door and raising said stud from the downwardly-directed slotted portion associated therewith and thereby releasing said stud for movement in the longitudinally slotted portion, thus unlocking the associated door, when the other end of each cord becomes wound upon the wind-up to which it is connected upon opening of the respective other door, and means for supporting both cords intermediate the two doors for free independent movement thereof.

4. An automatic door latch-releasing system including the combination with two doors having individual door jambs spaced apart, said doors being adapted to be independently opened, of releasable latch means upon the jamb of one door serving to lock the latter in the locked position of the latch means, operating means upon the jamb of the other door including a gear rotatably supported in the jamb of the other door, a rack on the latter meshing with the teeth of the gear in closed position of said other door and in a limited portion of its opening and closing movement, a further gear rotatably supported in the latter jamb and in effective position to be rotated by the first-mentioned gear, a cylindrical portion associated with and rotating with the further gear and serving as a wind-up drum having a cord connected at one end thereto, the other end of the cord being connected to the latch means in effective position to cause releasing of said latch means and thereby the unlocking of the first-mentioned door upon being pulled by being partly wound up on said cylindrical portion upon opening of said other door, and means for supporting said cord intermediate the two doors and allowing free movement thereof in both directions.

5. An automatic door latch-releasing system including the combination with two doors having individual door jambs spaced apart and said doors being adapted to be independently opened, of releasable latch means upon the jamb of one door serving to lock the latter in the locked position of the latch means, operating means upon the jamb of the other door including a spur gear supported for rotation on a vertical axis in the jamb of the other door, a rack fixed transversely upon the edge of the latter door meshing with the teeth of the spur gear in closed position of

said other door and in a limited portion of its opening and closing movement, a bevel gear rigidly rotating with said spur gear, a further bevel gear meshing with the first-mentioned bevel gear and having a substantially horizontal shaft mounted for rotation in the last-mentioned door jamb, clutch means upon the further bevel gear, a cylindrical clutch member slidably mounted on the horizontal shaft and having corresponding clutch means adapted in one position to engage with the clutch means on said further bevel gear, a spring mounted on said horizontal shaft normally tending to maintain the cylindrical clutch member engaged with the clutch means on said further bevel gear to cause both parts to rotate together, a cord secured at one end to a portion upon the cylindrical clutch means and the other end being connected to the latch means in effective position to cause releasing of said latch means and thereby unlocking of the first-mentioned door upon being pulled by being partly wound upon said cylindrical clutch member upon opening of said other door, and means for supporting said cord intermediate the two doors and allowing free movement thereof in both directions.

6. An automatic door latch-releasing system including the combination with two doors having individual door jambs spaced apart and said doors being adapted to be independently opened, 30 of a latch casing upon the jamb of one door having a longitudinally-slotted portion terminating in a downwardly-directed slotted portion, a latch bolt mounted in the latch casing having a stud projecting therefrom through the longitudinally slotted portion to be accessible for manually locking said bolt by shifting the stud down into the downwardly-slotted portion and causing the bolt to project from the jamb into locking engagement with the door, a spring in said 40 latch casing tending to return said bolt into released withdrawn position, operating means upon the jamb of the other door including a gear rotatably supported in the jamb of the other door upon a shaft adapting it for rotation on a 45

vertical axis, a rack fixed transversely upon the edge of the latter door and meshing with the teeth of the gear in closed position of said other door and in a limited portion of its opening and closing movement, a bevel gear rigidly rotating with said first-mentioned gear, a further bevel gear meshing with the first-mentioned bevel gear and having a substantially horizontal shaft mounted for rotation in the last-mentioned door jamb, clutch means upon the further bevel gear, a cylindrical clutch member slidably mounted on the horizontal shaft and having corresponding clutch means adapted in one position to engage with the clutch means on said further bevel gear, a spring mounted on said horizontal shaft tending normally to maintain the cylindrical clutch member engaged with the clutch means on said further bevel gear, a cord secured at one end to a portion upon the cylindrical clutch member and at the other end being connected to the latch means in effective position to cause releasing of said latch means and thereby the unlocking of the first-mentioned door upon being pulled by being partly wound upon said cylindrical clutch member on opening of said other door, and means for supporting said cord intermediate the two doors including a plurality of support members.
